INTERVALOMETER

William T. Van Horn, Oaklyn, N. J.

Application April 25, 1944, Serial No. 532,680

7 Claims. (Cl. 74—471)

(Granted under the act of March 3, 1883, as amended April 30, 1928; 370 O. G. 757)

This invention relates to devices which are manually or otherwise operable to actuate a series of mechanisms in a preselected order. Such devices are commonly called intervalometers.

One of the uses to which an intervalometer is put is that of releasing bombs or the like from aircraft. Several bombs are generally carried by an aircraft, some of the bombs overlying others, depending upon the arrangement of the bomb racks, bomb bay doors etc., and it is necessary that the doors be opened and the bombs be released in a particular order, so that a higher mounted bomb does not fall upon one which has not yet been released, or that a bomb is not released before the doors are open. Another factor entering into the proper sequence of release of the bombs is that many of the bombs carried are of such weight that they disturb the weight balance of the airplane when released. For example if the bombs are distributed on both sides of the fore and aft axis of the airplane, as under the wings, it is necessary that the bombs be alternately released first from one side and then the other, else the lateral balance of the airplane might be so disturbed as to throw it out of control if there is a substantial interval of time between releasing operations. While a separately operated control might be used for each release, there is danger of them being operated in improper order. Preoccupation of the pilot or operator with other simultaneous duties is a primary cause of such improper operation. By the use of an intervalometer it is assured that each operation will occur in its proper predetermined sequence, even though the elapsed time for an entire sequence to be completed may be only a few seconds. An intervalometer may be moved throughout its entire range in a single stroke or in any desired number of partial strokes. In any event there is assurance that the release operations will occur in their proper predetermined sequence. Thus when the handle is moved through part of its range it will actuate the releases which it passes during such movement. When it is moved further it will merely resume the actuation of the remaining releases in their proper order.

It is the purpose of my invention to provide an improved intervalometer which may be moved throughout its stroke in one continuous operation or in interrupted operations, there being releasable means operable to hold it at the end of any interrupted operation, and wherein the actuating means is positively moved towards its

final position by the intervalometer handle during its movement, whereupon the actuating means is removed from the path and influence of the handle.

Other objects will become apparent as the description progresses in connection with the annexed drawing, in which:

Fig. 1 is a side elevation of the intervalometer;

Fig. 2 is a top plan view of the device shown in Fig. 1;

Fig. 3 is a partial side elevation similar to Fig. 1, showing elements actuated by the intervalometer;

Figs. 4, 5 and 6 are partial sectional views in a plane perpendicular to that of Fig. 1, and showing a sequence of events in the operation of one of the elements of the intervalometer; and

Fig. 7 is a partial sectional view, taken in the plane 1—1 of Fig. 4 and looking in the direction of the arrows.

As shown in Fig. 1, a flat circular plate 1 has three lightening holes therein, defining radial spokes 2. A handle 3 having a knob 4 at its outer end is pivotally attached to the plate at its center by means of a bolt 5 or the like. Integral with the handle 3 is a lever arm 6 which lies parallel to but slightly spaced from the plane of the plate 1 as better shown in Figs. 4 to 6.

A flange 7 is attached to the periphery of the plate 1, extending at right angles thereto and for about three-quarters of the circumference. On its bottom portion it has a guide slot 8 in which the outer end of the lever arm 6 slides. On its top portion a slot 9 provides both a guide and a stop or detent means for the handle 3. As shown in Fig. 2 the slot 9 is smooth on its outer side. On the side towards the plate 1, the slot has a series of spaced notches 10 which are of a length sufficient to permit the entrance of the handle 3. The handle 3 is slightly bowed and is so tensioned that it normally bears against the notched side of the slot 10. In order to move the handle around its pivot 5 it must be pushed away

from the notches and held against the smooth side of the slot 9 while its angular position with respect to the plate 1 is changed. The handle can be moved from one to the other end of the slot 9 in one stroke by holding it against the smooth side of the slot. When it is desired to move it only from one notch to the next it is disengaged from the notch, shifted, and allowed to fall into the next desired notch under its own tension. The distance between the notches is

determined by the positions of devices engaged

by the lever 6 in its movement, as will be described.

On its bottom portion the circular plate 1 has a series of spaced slots 11, 12, 13 and 14. These slots are identical in dimensions. Each has a long narrow portion, and at one end a short wider portion. Taking the slot 11 of Fig. 1 for example, it has a long narrow portion 15 and a short wider portion 16. Each of the slots 11 to 14 has its longest dimension perpendicular to a radial line from the bolt 5 and intersecting the slot approximately at its mid-length.

A latch, shown in detail in Figs. 4 to 7, slides in each slot 11 to 14. Each latch comprises a T shaped member having a cross piece 17 which overlies the edges of the narrow portion 15 of the slot, and a stem portion 18 which slides within the narrow portion of the slot. A pair of angle plates 19 and 20 have their longer legs permanently fastened as by welding, to the stem portion 18, their short legs extending outward from the stem to form flanges which prevent the stem portion of the latch from being pulled out of the narrow portion 15 of the slot, as best shown in Fig. 7. A dog 21 forms part of each latch and is pivotally mounted between the angle plates 19 and 20 by means of a pin 22 which may have one end threaded into one of the angle plates. As best shown in Figs. 4 and 7, the dog has a thin portion which lies between plates 19 and 20 and passes through the narrow portion 15 of the slot in the plate. At its free end the dog has an enlarged portion 23 which is too wide to pass through the narrow portion 15 of the slot but which can pass freely through the wide portion 16 thereof. The thin portion of the dog joins the enlarged portion at a sharp shoulder which rests upon the sides of the narrow slot 15 when the dog is in the position shown in Figs. 4 and 7. When the dog is in this position the entire latch including the dog can slide in the narrow slot and the dog will hold the relative position shown in Fig. 4 because of the shoulders previously described. While in this position the enlarged portion 23 is engageable by the lever arm 6 in its movement.

As illustrated in Figs. 4 to 6, as the lever arm moves the latch to the right, or towards the wider portion 16 of the slot, the latch will merely slide along with the dog in the position of Fig. 4. A control cable or rod 24 is fastened by any suitable means to the stem portion 18 of the latch, and is therefore pulled as the latch is moved. At its other end the cable 24 is fastened to any means, indicated by the pivoted lever 25 of Fig. 3, which means it is desired to actuate by the intervalometer, and which means in turn may operate a bomb release or the like.

During the movement of the latch to the right, the enlarged portion 23 of the pivoted dog reaches the wider portion 16 of the slot. Since the lever arm acts on the outer free end of the pivoted dog, it exerts a clockwise turning moment upon it, as viewed in Figs. 4 to 6, thus the portion 23 of the dog is unrestrained by the narrow slot 15 when it reaches the wide slot 16, and passes therethrough as shown in Fig. 5. While the enlarged portion 23 is passing through the slot its curved portion will engage the end of the slot and slide thereon as the lever arm 6 passes over and forces the dog through the slot. This results in a camming action of the portion 23 against the slot which forces the sliding portions of the latch slightly back to the left. Thus the entire latch is slightly farther to the left in the position of

Fig. 6 than it was when the pivoted dog first began to pass through the wide portion of the slot, as shown in the position of Fig. 5.

As shown in Figs. 1, 3 and 7, the cross piece 17 of the T shaped member is wider than the enlarged portion 23 of the dog 21, which portion is narrow enough to pass freely through the wide portion 16 of the slot. The width of the cross piece 17 is barely less than that of the wide slot 16 so that it can be forced through the wide slot when properly juxtaposed thereover. This force fit prevents the cross piece 17 from accidentally passing or falling through the wide portion 16 of the slot. This construction allows the pre-fabrication of the entire latch and its assembly to the plate 1 by passing the cross piece 17 through the wide slot 16. It also permits the removal of any number of unused latches from the plate when they will not be needed for a particular installation.

As shown in Fig. 1, the slots 11 and 13 are a shorter radial distance from the pivot bolt 5 than are the slots 12 and 14. This is to provide a closer angular grouping of the slots than if they were arranged end to end at the same radial distance from the center. With this arrangement the slots are overlapped and the lever arm 6 may begin its engagement with a second latch before it has been finally released from its engagement with a first one.

The notches 10 in the slot 9 which guides the handle 3 are so angularly spaced that the handle will fall into one of them just after one of the latches in slots 11 to 14 has been released. Thus the operator is assured that a release has been actuated when he has advanced the handle from one notch to the next, or past several notches to any succeeding notch.

It will be understood that the above description and accompanying drawing comprehends only the general and preferred embodiment of the invention and that various changes in construction, proportion and arrangement of the parts may be made within the scope of the appended claims without sacrificing any of the advantages of the invention.

The invention described herein may be manufactured and used by or for the Government of the United States of America for governmental purposes without the payment of any royalties thereon or therefor.

I claim:

1. An intervalometer comprising a circular plate; an operating handle; pivot means attaching said handle to said plate; a lever movable with said handle; a series of angularly spaced elongated slots in said plate, having their longest dimension substantially perpendicular to a radius from said pivot; latch means slidable in said slots and arranged to be engaged and moved by said lever during its movement and to disengage themselves from said lever at the end of their movement.

2. An intervalometer comprising a plate having a series of spaced slots therein; latches slidable in said slots, each latch having a dog pivotally attached thereto; a member mounted for movement parallel to the surface of said plate and operable to engage said dogs during its movement; said slots having narrow portions for sliding engagement with said dogs and wider portions permitting the passage of said dogs therethrough and their disengagement from said member, whereby said latches are moved while said member engages and moves said dogs, but

are unaffected after said disengagement; and means attached to said latches for connecting them to devices arranged to be actuated thereby.

3. The device described in claim 2 wherein detent means are provided to stop the movement of said member after it has become disengaged from any of said dogs.

4. In an intervalometer; a plate having an elongated slot therein, said slot having a short end portion of greater width than the remainder; a latch comprising a portion mounted in said slot for sliding movement therein and having a dog pivotally attached to said portion, and elements on either side of said plate preventing the withdrawal of said dog from said slot except at the wider portion thereof; said pivotally attached dog being of such width as to pass only through the wide portion of said slot; and a movable member engageable with said dog to slide said latch along said slot until said dog passes through the wide portion of said slot; said latch being

adapted to be connected to a device which is actuated by the movement of the latch.

5. The device of claim 4 wherein said plate is circular and said movable member includes a handle extending beyond the periphery of said plate; and a flange on the periphery of said plate having a pair of guide slots through which said movable member and said handle extend.

10 6. The device of claim 4 wherein opposed edge portions of said plate are provided with guide slots for said movable member and for said handle.

15 7. The device of claim 4 wherein opposed edge portions of said plate are provided with guide slots for said movable member and for said handle, the guide slot for said handle having detent means to stop said handle following the disengagement of said movable member from said dog, and said handle being disengageable 20 from said detent means.

WILLIAM T. VAN HORN.
